UNITED STATES PATENT OFFICE.

HARRY M. PFLAGER, OF ST. LOUIS, MISSOURI, ASSIGNOR TO DOUBLE BODY BOLSTER COMPANY, OF ST. LOUIS, MISSOURI, A CORPORATION OF NEW JERSEY.

CAR-FRAME CONSTRUCTION.

1,080,163.

Specification of Letters Patent.

Patented Dec. 2, 1913.

Application filed November 8, 1912. Serial No. 730,220.

To all whom it may concern:

Be it known that I, HARRY M. PFLAGER, a citizen of the United States, residing at St. Louis, Missouri, have invented a certain 5 new and useful Improvement in Car-Frame Construction, of which the following is a full, clear, and exact description, such as will enable others skilled in the art to which it appertains to make and use the same, reference being had to the accompanying drawings, forming a part of this specification, in which—

Figure 1 is a front elevational view of a car end frame showing certain features of 15 my improved construction. Fig. 2 is a plan view partly in section taken on line 2—2 of Fig. 1. Fig. 3 is a side elevational view looking at the right hand side of Fig. 1, and illustrating the application of the device to 20 the car platform frame. Fig. 4 is a side elevation partly in section on line 4—4 of Fig. 1.

This invention relates generally to railway car construction, and more specifically 25 to the one-piece, cast metal car end frames of the type disclosed in Patent #917,716, issued April 6, 1909, and #929,705, issued to me August 3, 1909.

One of the most important features in the 30 construction of the present types of railway cars, and particularly those used for the transportation of passengers, mail and express matter and baggage, is the reinforcing of the ends of the cars so as to provide an exceptionally strong and rigid construction which will effectually resist end 35 shocks and crushing stresses delivered to the ends of the cars. The purpose of such construction is to overcome the tendency 40 of the cars to telescope in case of collisions and to afford the greatest possible degree of safety to the occupants and contents of the cars.

My improvement contemplates a comparatively light-weight, strong and durable one-piece cast metal structure, formed, braced and connected to the car underframe and superstructure so as to combine therewith in resisting end shocks and crushing stresses 50 imparted to the end of the car, thereby providing a construction which is anti-telescopic in effect.

One object of my invention is to provide an end frame of the sort described having 55 formed therein end door posts cast with

parts specially formed to accommodate the vestibule diaphragm, and to provide parts on the end frame specially formed to accommodate the supports of the vestibule diaphragm.

Another object of my invention is to provide in an end frame of the class described which is cast with integral upright and transverse members, specially formed parts which are adapted to accommodate and support the shaft of the hand wheel brake or similar working parts of the car equipment.

By reference to the drawing it will be seen that my invention contemplates an integrally cast end frame having the lower 60 member 1, the upper member 2, door posts 4, upright members 5 and transverse members 6. The end frame as shown is provided with a central door opening, and is adapted for use in passenger cars and others 65 employing the end door, the door posts are formed with deep web portions 7 and finished at their outer extremities with the broad facing flanges 8. The flanges 8 afford an attaching place for the vestibule 70 diaphragm 9 illustrated in Fig. 2, which is secured thereto by stay strips 10 bolted to the flanges 8 by the bolts 11. The upper transverse member as shown in these figures is provided with the flanges or brackets 75 12 in which are formed the apertures 14 which are provided to accommodate the stems of the diaphragm buffers. Formed on the upright or transverse members of the end frame to one side of the door opening are the flanges or brackets 15 in which are provided the apertures 16. These apertured flanges are provided for the purpose 80 of accommodating the shafts for the hand brake which is positioned at the end of the 85 car.

From the foregoing it is obvious that my improved car construction provides a structure which is particularly adapted to prevent telescopic movement of the end frame 90 relative to the underframe, and that the several features described especially adapt cast steel end frames to the accommodation of various elements of the car equipment.

I am aware that by changes other forms 100 of my invention may be produced, and I therefore do not intend that my invention be limited to the specific form shown and described, but that it be construed to cover all obvious changes and modifications.

I claim—

1. In car construction, an integrally cast end frame formed with upright and transverse members, a pair of the upright members 5 performing the functions of door posts, brackets integral with said door posts at predetermined points near their upper ends, and which brackets are perforated to receive the diaphragm buffer stems.
- 10 2. In car construction, an integrally cast end frame formed with upright and transverse members, brackets formed integral with one of the upright members at predetermined points, and which brackets are 15 provided with apertures adapted to form bearings for the hand brake shafts.
- 10 3. In car construction, an integrally cast end frame formed with upright and transverse members, brackets formed integral 20 with certain of said upright members at predetermined points, and which brackets

are perforated to provide bearings for the diaphragm buffer stems, and the hand brake shafts.

4. In car construction, an integrally cast 25 end frame, provided with an end door opening, door posts integral with said frame at the sides of said door opening, which door posts are substantially wider than the width of the end frame, and laterally projecting 30 flanges integral with the outer ends of said door posts, which flanges are adapted to receive the inner ends of the flexible diaphragm.

In testimony whereof I hereunto affix my 35 signature in the presence of two witnesses, this 22d day of October, 1912.

HARRY M. PFLAGER.
